SUPERCHARGER FOR GAS ENGINES

Warren F. Stanton, Pawtucket, R. I.; Gladys Perry
 Stanton administratrix of said Warren F. Stanton, deceased

Application June 29, 1932, Serial No. 620,021

19 Claims. (Cl. 123—119)

An object of my invention is to provide a supercharger for gas engines which, besides being advantageous in other respects, will be especially suited for automobile engines, in that engine and transmission will be safeguarded from abuse in the operation of the supercharger; will deliver measured quantities of air to the engine from the lowest to the highest engine speed; will be of high efficiency especially when throttled; and which may have characteristics of construction in regard to weight and overall dimensions especially fitting it for use in an automobile. Other objects and advantages of my invention may be understood by those skilled in the art when embodiments of my invention hereinafter set forth in detail are understood.

In the drawings—

Fig. 1 is a side elevation of enough of the power plant of an automobile to illustrate an embodiment of my invention applied thereto;

Fig. 2 is an end elevation (looking in the direction of the arrow in Fig. 4) with parts in section of what I regard as the best type and construction of air-pump for a supercharger;

Fig. 3 is a top plan view of such pump with parts in section;

Fig. 4 is a vertical longitudinal section to such pump taken substantially on line 4—4 of Fig. 2;

Fig. 5 is a vertical section on the line 5—5 of Fig. 4;

Fig. 6 is a detail view of the pump valve controlling device taken substantially on line 6—6 of Fig. 5;

Fig. 7 is a front view of Fig. 6 with the speed governor 42 and its parts removed.

Fig. 8 is a detail view of a vacuum device for controlling the amount of supercharge;

Fig. 9 is a view of a fuel pump controlled by the supercharger and which may be used; and

Fig. 10 is a graph showing a characteristic curve which forms the basis for the desired action of the supercharger.

My invention consists in that which is described by or included within the scope of the appended claims.

In producing the embodiment of my invention shown in the drawings and designing the mechanism, I have taken into account the fact that all automobile inventions have speed ranges in which they are especially sensitive to detonation or such speed ranges, say from 450 to 1200 revolutions per minute, and I have provided a suitable degree of supercharge for each speed condition. This is exemplified by the graph shown in Fig. 10 which gives the factors of per cent of supercharge and revolutions per minute and which shows the amount of charge increase at the extremely low speed over the intermediate low speeds and increase from low intermediate speed to the highest desirable in the case of a

particular engine and then rapid decrease as the engine passes the safe or desired maximum speed. It is possible with my invention to secure the maximum or highest output and efficiency from a given engine with freedom from injuries or destruction by abuse by the driver in the use of the supercharger. To illustrate this, it may be explained that with a variable speed transmission that includes say four speeds it is desirable only on the fourth gear speed and to a limited degree on the third gear speed that the full power of the engine be developed by the use of the supercharger. Thus on the reverse and first or second speeds the transmission drive shaft and other parts involved are not subjected to excessive and dangerous stresses.

Referring to Fig. 1, it will be seen that the supercharger pump 18, which is shown in detail in Figs 2-5, is mounted forward of the engine 10 and immediately forward of the radiator 11 at 20 the lower half thereof, and which is a false front 13 which reaches over and covers said pump. This location of the pump has such advantages as to make use of what is otherwise wasted or not utilized space, assures maximum cooling without 25 impairing the efficiency of the radiator by shrouding or covering, it enables a simple drive connection with the engine, which is by means of a shaft 14 with two universal joints 15, one in advance of the other and the forward joint 30 30 making the connection with the crank-shaft 16. The front location of the pump assures the cold-est possible temperature and that is of great importance in a supercharger since supercharged air must be supplied to the engine at the lowest 35 possible temperature.

The pump is shown attached to the chassis at back and front, the back attachment being to a cross member 158 and the front being by brackets 160 reaching forward to and engaging a cross 40 tube 170.

Connections are made between the air pump or compressor and the engine to transmission and other controls and fuel pumps automatically to adapt the supercharge to the engine conditions, as exemplified in the case of the graph above referred to, and these things will be described hereinafter.

Describing first the construction and operation of the pump, having reference to Figs. 2-5, it will 50 be seen to comprise three equi-distant radial members each comprising a finned cylinder 18 and piston 19 all connected to the crank-shaft 16, which as has been explained, is connected with and receives power from the gas engine to reciprocate the pistons in their cylinders. The three pump members are alike, each being double acting and having a valve 21 for controlling the pump intake and discharge or outlet, the valves of all three being connected with a common eccentric 55 60

30 on the crank-shaft 16 and the compressed air outlet or discharge from all three valves 21 being delivered to an annular chamber 20 in the crank case 18^a having three outlet ports 20^a located in the space between the cylinders 18 and from which delivery pipes may extend. One of these ports 20^a is at the bottom of the crank case 18^a (Figs. 1 and 2) and preferably a pipe P is connected with that port and leads to the carburetor 19 and to intake manifold, the other two ports being, of course, closed by cover plates 20^b (see Figs. 2 and 4).

15 The pump valve 21, shown, is a slide valve of a form common in steam engine practice located in a valve chamber 22 and at opposite ends of each cylinder 18 are two ports, one 23 leading from the valve chest or chamber 22 to the outer end of the cylinder and the other 24 leading between the inner end of the cylinder and the valve chest; 20 and between such ports there is an intake or induction port 26, in communication through opposite twin passages 27 with an annular chamber 28 (Figs. 3 and 4), adjacent to the discharge chamber 20 and concentric with the crank shaft 18^a 25 from which latter opens the outside air intake or induction ports 29 in the external wall of such chamber. One of the ports 29 is shown (Figs. 1 and 2) having an air funnel 29^a thereover, while the other two are closed by cover plates 20^b, which 30 also cover the closed discharge outlet ports 20^a. The arrangement of intake and outlet ports and passages gives such great capacity of air inlet and outlet as to contribute to the reduction of pumping losses to the minimum. The minimum 35 of work is required of the pump for a given quantity of air under all loads or air quantities delivered to the engine, and but little force or power is required for shifting the pump valves by the action of the eccentric and automatically to 40 change or adjust and hold the eccentric in the proper position to give the desired air output with respect to the degree of supercharge that happens to be called for by the engine requirements. Indeed, the forces of inertia, during acceleration, 45 tend to prevent or hold down the degree of supercharge under conditions which require diminution of supercharge and friction of the engine valves and other parts produce the same effect. All this, of course, is in the interest of protecting or safeguarding the engine by the use of supercharge 50 that is excessive and which necessarily results in damage or injury to the engine.

When reducing the quantity of air output, the chief work done by the air compressed and delivered to the engine is that required to deliver the quantity of air to the engine plus the air friction in flowing into and out of the ports or passages. Providing air ports or passages of large area as I do, the friction losses are low and the total efficiency of the pump is high. The reciprocating type of pump, which I employ, has marked advantage in respect of efficiency and simplicity of mechanism; and of particular importance in this connection is the reciprocating type of pump 60 when, as is the case of my invention, it is employed with automobiles requiring variable speed with considerable speed ranges. The centrifugal compressor, for example, is unsuited for any such use.

65 70 75 As I have already pointed out, the supercharger output is automatically controlled in correspondence with the speed and power requirements of the engine, and this is rendered effective by connections with the driver operated control so that, for example, the driver cannot cause the supply

to the engine of a supercharge in excess of the engine requirements.

The slide valve operating eccentric is a drum 30 rotatable on the crank-shaft, on which for each valve is an eccentric strap 31 (preferably made of twin pieces of pressed metal), the straps in each case being connected by a rod 32 with the slide valve 21. The connection between the rod and slide valve is adjustable for accurate timing of the valve. By this eccentric connection the three sets of valve reciprocating members are maintained in the same plane and balancing of all thereof, is easily and simply done by balance weights 33 secured to opposite sides of the eccentric drum.

15 Referring particularly to Figs. 6 and 7, which show the eccentric connection with the crank-shaft, it will be seen that slideable axially in a longitudinal passage 16^a in the crank-shaft 16 is a round rod 34 that extends concentric with the eccentric drum 30 and upon opposite sides thereof. Fixing to and projecting radially at one end from said rod 34 is a pin or key 35, which extends through a longitudinal slot 37 in the crank-shaft 16 (see Figs. 6 and 7) and engages a spiral groove 36 in the inner circumference of the eccentric drum 30, so that by the axial movement of the rod with said key (the key being restrained from turning by engagement with the longitudinal slot 37 in the crank-shaft 16) the eccentric drum will 30 be rotated on the crank-shaft and held in whatever position to which it may be rotated and thus the pump valves shifted and the timing thereof altered with the result that the compressed air output from the air pump or compressor is varied. 35

The rod 34 is acted upon at its inner end by an expansion coil spring 38, which tends to move the rod in the direction to shift the eccentric drum from a position that results in maximum compressed air output to positions diminishing that output; and provision is made to control movement of said rod so that automatically shifting of the eccentric drum will be controlled, for example, by the speed of the engine. Describing what is shown best in Figs. 5, 6 and 7 of the drawings, for this purpose it will be found that at the outer end of the rod 34 is a diametrically extending pin 39, whose opposite ends project beyond the rod and engage inclined cam faces 40 in the outer end of a collar 41. The collar 41 is rotatably mounted on the crank-shaft 16 and has its angular position, with reference to the pin 39 shifted, according to the speed of the engine, by a centrifugal governor secured to the crank-shaft. This governor includes a spore-like member 42 surrounding and made fast by pin 42^a to the crank-shaft 16 and interposed between the drum 30 and the collar 41, and to which is pivoted a weighted arm 43 by an eccentric pin 44. The weight 43 is subjected to a centripetal tendency by a coil spring 45 attached at one end to the weighted arm and at the other end to a pin 46 on the member 42. The pins 44 and 46 pass through arcuate slots 41^a in the collar 41 and a link 47 connects the weighted arm 43 to cam collar 41, so that motion of the weighted arm is thereby imparted to the cam collar 41. Preferably for balancing purposes, in practice, the weights, springs, and links are duplicated. 50 55 60 65 70 75

From the above, it will be seen that the rod 34 under the pressure of the spring 38 acting thereon, is free to move outward away from the cam faces 40 of the collar 41, but movement in the opposite direction is limited by the position of the inclined cam faces 40 of the collar 41; and this 75

condition prevents movement of the rod 34 against its spring pressure to shift the eccentric drum to a position which will increase the compressed air output or the supercharge.

5 The device consisting of the pin 39 and the cam collar 41, thus imposes a maximum limit on the degree of supercharge and limits supercharge at the will of the driver to less than that maximum. This is accomplished by having the outer 10 end of the rod 34 co-act with a finger 48, which has a control connection with the accelerator or driver's rod 54. The finger 48 is carried by a sleeve 48^a rotatably mounted on a rock shaft 49 and is operatively connected to one end of a torsion spring 50 (see Fig. 3), the other end of said 15 spring 50 being operatively connected to a collar 51 pinned to the shaft so that there is this spring connection between the rock shaft and said finger. On the shaft 49 is pinned a collar 52 having a 20 shoulder s on the side next to the sleeve 48^a adapted to engage a similar shoulder on the sleeve and so arranged that, by the rotation of the shaft 49 in the direction of the arrow x with the two shoulders in engagement, the finger 48 may be 25 swung away from the end of the rod 34 and, thus, determine the position of the rod when moved by its spring 38 and, corresponding, of the eccentric drum and the timing of the air pump valves 21. Pinned to the rock-shaft 49 is a crank 53, to the 30 outer end of which as shown in Figs. 1 and 3 is connected the forward end of the driver operated control rod 54. It will be seen that force applied to the shaft 49 from the driver's rod 54 to swing the finger 48, in the direction of the arrow 35 y to move the rod 34 inwardly against the pressure of spring 38 to increase the supercharge, is transmitted to the finger from the collar 51 through the spring 50, and thus the force applied to the finger is limited, regardless of the wishes of the driver in controlling the supercharge, as the 40 strength of the spring 50 is inferior to the force exerted by the centrifugal governor 42 in rocking the cam collar 41 with reference to the rod pin 39. Movement of the rod 34, beyond the maximum limit fixed by the position of the cam collar 41, cannot take place under the power of the 45 spring 50 because it is opposed by the centrifugal governor 42 acting on the cam collar 41.

The driver's control rod 54 is operatively a part 50 of the accelerator rod 55, which as usual is connected to the throttle valve by a crank arm on the valve shaft 56. On said shaft 56 is a cam arm 57, against the side of which bears the closed end of a tube 58 telescoping over the adjacent end of the rod 54. A helical spring 60 is disposed between the inner end of the tube 58 and a collar 59 on said rod 54 and which thus provides a yielding section in the rod allowing opening of the throttle valve, even though rod 54 resists movement, because of the action of the centrifugal governor 42 on the cam collar 41, as hereinbefore described, to limit the degree of supercharge to less than a certain maximum. Obviously, the throttle valve may be operated by the accelerator within the limits 65 automatically fixed to increase the engine power and also by changing the time of the compressor valve through movement of the eccentric drum shifting rod 34 actuated by the finger 48.

I also provide a safety control in connection 70 with the transmission in order to restrict supercharge, when the gear connections are in the lower speeds or in reverse which should not be subjected to excessive or great stresses from the engine. This is of especial importance because, 75 while on the higher gears, say fourth and third

of a four speed engine, the parts concerned are sufficient to withstand the stresses from a supercharged engine, which is not the case usually as to the lower speeds and to reversing.

Referring to Fig. 1, which shows in part the 5 transmission, there is a pivoted lever arm 61 with its free end in position to be engaged by the gear selector rod 62 so as to partake of the movement of said rod when it is shifted to the various 10 positions required for changing the forward gears or for reversing. To said lever 61, is pivotally connected one end of a rod 63, whose other end is pivoted to a crank arm 64 connected to the pivot of a cam finger 65, which co-acts with a collar 66 fixed on the driver's control rod 54. The 15 position of the cam finger 65 determines whether, and the extent which, the rod 54 may be moved to operate the eccentric drum controlling finger 48; and the position of the cam finger 65, as will be seen, is dependent upon the position of the 20 gear shifting rod 62. When the fourth and third gears are in use, the full supercharge power or a slightly reduced power may be delivered from the air compressor, while at the lower speeds and for reverse the power of the engine is restricted to 25 safeguard the mechanism. Excess power from the supercharger, which might be injurious, is thus guarded against when the transmission is in neutral, first, second, and reverse positions, but full power from the supercharger may be used 30 only when the car and engine conditions render it safe and desirable.

It is also important in a supercharged engine for spark control. The spark must be retarded or advanced according to the degree of super- 35 charge and that can be made dependent upon a pre-determined charged density, according to a graph based upon the particular engines characteristics in relation to sensitiveness to detonation affected by speed and considering the transmission gear used. 40

Referring to Fig. 1, supercharged control in relation to the time of spark is illustrated. By a pipe 67, compressed air from the supercharger on the way to the carburetor is taken by connecting 45 such pipe with the pipe P, which connects the compressor with the carburetor, and the pressure thus taken is delivered to one side of a dia- phragm 68 in a closed chamber 69, the diaphragm being acted on the opposite side by a spring 70, 50 and from that side of the diaphragm a link 71 ex- tends to a bell crank lever 72 having a cam sur- face 73 bearing against a rod 74 connected with the timer 75, said rod 74 being pressed against the cam 73 by a coil spring, 76. The timer may have 55 a standard internal centrifugal device for spark control (not shown) and, if so, its action is modi- fied by the operation of the cam lever 72, accord- ing to the supercharged pressure. It will be ob- served that I do not use the carburetor manifold 60 vacuum, but I use super-atmospheric pressures existing before the carburetor 79 is reached.

Change of carburetor adjustment becomes de- 65 sirable when supercharging and according to the charged density, and this may be accomplished as shown in Fig. 1 by the action of the diaphragm 68. From the bell-crank 72 a rod runs to the arm 77 of a rotary cam 78, which acts upon the stem 79^a of the carburetor needle valve and in oppo- sition to a spring 80 on such stem. 70

For a regulation of the fuel pump according to the charge density, there is provided in the case of a fuel pump 81, such as shown in Figs. 1 and 9, a pumping spring, the tension of which is automatically increased with the increase of the

charge density. The pump, shown in detail in Fig. 9, is operated from the usual engine cam shaft actuating a lever 82 to compress the pumping spring against an air piston 84 in a cylinder 85, the spring tension determining the pressure in the float chamber of the carburetor 79. The pressure on the fuel at the carburetor of a non-supercharged engine is small, being only a few ounces, but with a supercharger the pressure is considerably greater, as much as a number of pounds. The tension of the pumping spring 83 is increased correspondingly with the increase of the charge density by admitting pressure from the supercharger pipe P through a tube 86 to the cylinder 85. The spring 83 acts upon one side of a diaphragm 81, the other side of which draws fuel from a valve inlet pipe 88 and forces it, under the desired pressure, to an outlet pipe 89 which conveys it to the float chamber of the carburetor 79.

As shown in Fig. 8, a supercharge control means may be employed that utilizes the vacuum, for example the vacuum at the throat of the carburetor venturi. From such vacuum point a pipe 90 extends to a chamber 91 having a flexible diaphragm 92, which within the chamber is exposed to the reduced pressure and is pressed outward in opposition thereto by a coil spring 93. A link 94 connected at one end to the diaphragm 92 is connected at the other end to the lever arm of a rotary cam 95 which has several cam surfaces that co-act with a collar 96 fixed to the diaphragm control rod 54. The co-action of the cam surfaces 95 and the collar 96 determine the extent of movement of the control rod 34 for shifting the position of the eccentric drum 30 which regulates the movement of the valves 21 of the compressor 18. Of course, the vacuum at the carburetor throat bears a relation to the engine speed.

In the interest of economy of construction, lightness in weight, and compactness, the air pump shown in the drawings has certain advantageous features of construction; thus, the crank 45 shaft is a built-up shaft; the connecting rods 97 are of the boltless type which makes counter-balancing simple by counter-weights 98; the pump piston 19 has a reduced portion or diameter 19a which slides in a cylindrical reduced extension 99 at the inner end of the cylinder 18 providing a double-acting piston with its cross head and piston as a unit; and cylinder 18 has an integral or unitary head and is bolted to the crank case 18a by a bolt 18b.

Suitable means for lubrication of the air pump parts, not necessary to be shown and described, are employed. However, it should be pointed out that oil supplied to the crank-shaft bearing is also supplied to and surrounds the inner end of the eccentric drum adjusting rod 34 through a hole 100 in the crank shaft 16 to an annular groove 101 in the end portion of said rod 34, which groove provides a dash-pot piston 102 on the end of said rod 34. The oil pressure on the rod supplements the force of the spring in moving said rod in one direction.

It will be understood that in any delayed timing position of the valve moving eccentric drum 30, the displaced air under pressure in the valve chest is sucked or drawn back through the upper port leading into the cylinder 18 and into the space above the piston, and at the same time air below the piston is forced through the lower port back into the intake chamber.

Because of the tendency of engines to detonate

at low intermediate speeds, the compression ratio or the degree of supercharge is lower than is possible at other speeds and this limits the power obtained from a given engine to a lower value than is otherwise possible, some power being lost at extremely low speed and a gain in power being possible without difficulty.

One of the advantages from mounting the air compressor or supercharger at the front end adjacent the radiator is that when radiator shutters are provided to control the temperature of the engine, the temperature of the supercharger is also controlled. To reduce blanketing of the radiator by the air compressor to the minimum, the three cylinders are arranged so that one is uppermost and in a vertical position, while the other two extend downward and outward.

That which is claimed is:

1. The combination of a gas engine having a variable speed transmission, a supercharger for the engine, and means that control the supercharge delivered to the engine operative when certain transmission ratios are used comprising a movable member of the transmission to change the driving connection from the engine, manual means to control the supercharge to the engine having a to and fro moving element, and stop means to coact with the said element shiftable relative thereto, and an operative connection between said movable member of the transmission and said stop means.

2. The combination with a gas engine, of a supercharger therefor, manually operated control means for the engine and supercharger, and an automatic stop means which prevents operation of the supercharger at the will of the operator, said manually operated control means and said stop means comprising movable members, such member of the manual means being movable at will, and the member of the automatic means being shiftable to different positions, and an operative connection between an engine driven element and said automatic means member.

3. The combination with a gas engine, of a supercharger therefor, manually operated engine control means, automatic means which imposes a maximum limit on the degree of supercharge and prevents a supercharge by said manually operated engine control means beyond such maximum, and comprising an automatically supercharged controlling member and a manually controlled member having a loose operative connection therewith.

4. The combination with a gas engine, of a supercharger therefor, having engine controlled automatic means to determine flow from the supercharger to the engine and including a to and fro movable member and automatic means to arrest movement of such member in one direction, manually operated engine control means and a to and fro movable element whose movements are controlled thereby, said element and said member being engageable and said member serving to arrest movement of said element in a direction that would increase the supercharge flow to the engine.

5. The combination with a gas engine, of a supercharger therefor, manually operated engine control means, automatic means which imposes a maximum limit on the degree of supercharge and prevents a supercharge by said manually operated engine control means beyond such maximum, and comprising an automatically supercharged controlling member and a manually con-

trolled member having a loose operative connection therewith and with said manually operated engine control means.

6. A combination of a gas engine, of a supercharger therefor, means connected to the supercharger for varying the degree of supercharge delivered to the engine, manually operated control means connected with the supercharger to increase or decrease the supercharge thereto, and automatic means responsive to the speed of the engine for preventing a supercharge by said manually operated control means beyond the maximum requirement of the engine relative to the speed thereof.

15 7. The combination of a gas engine and a speed transmission, of a supercharger, speed responsive means operated from said engine for controlling the supercharge output in correspondence with the power requirements of the engine, manually operated engine control means for accelerating or retarding the engine and connected with said supercharger for increasing or decreasing the supercharge thereto, and means actuated from the transmission, when certain transmission ratios are used, for preventing a supercharge from the operation of the manually operated engine control means beyond the maximum engine requirements.

20 8. A device as set forth in claim 6, further characterized by a carburetor operatively connected with the engine, and means controlled by the pressure in the carburetor for preventing operation of the manual control means to supply a supercharge beyond the maximum of the engine speed requirements.

25 9. A device as set forth in claim 6, further characterized by an ignition timing means operatively connected with the engine, and automatic means actuated by the pressure in the supercharger manifold for retarding or advancing the timing of the ignition means of the engine and for regulating the needle valve of the carburetor thereof.

30 10. The combination with an internal combustion engine, of a supercharger actuated from said engine, valve means actuated from said engine for controlling the output from the supercharger to the engine, shiftable means for regulating the movement of said valve means whereby an increased or decreased supercharge may be delivered to the engine, manual control means for the engine for increasing and retarding the operation thereof and further connected with the valve regulating means of said supercharger for increasing the supercharge to the engine, and speed responsive means actuated by the engine for rendering ineffective the operation of the manual control means of said supercharger beyond the maximum speed requirements of the engine.

35 11. The combination with an internal combustion engine, of a supercharger actuated from said engine, valve means actuated from said engine for controlling the output from the supercharger to the engine, shiftable means for regulating the movement of said valve means whereby an increased or decreased supercharge may be delivered to the engine, manual control means for the engine for increasing and retarding the operation thereof and further connected with the valve regulating means of said supercharger for

increasing the supercharge to the engine, and means responsive to the speed of the engine for rendering ineffective the operation of said manually operated engine control means on the valve regulating means of the supercharger beyond the maximum requirements of the engine speed, and stop means rendered effective when certain transmission ratios are employed for limiting the supercharge increasing movement of the manual control means.

40 12. In a supercharger for engines, an actuated mechanism for controlling the output of supercharge to the engine, means for regulating the controlling mechanism for increasing or decreasing the supercharge, manually operable engine control means arranged to operate said regulating means, and means responsive to the speed of the engine for limiting the operation of said manual control means from operating said regulating means beyond the maximum speed requirements of the engine.

45 13. In a supercharger for engines, a compressor, valve means controlling the output of the compressor to the engine comprising a rotary shaft carrying an eccentric drum, a rod slidably carried in the shaft, a groove and pin connection between the rod and drum, said groove being oblique to the axis of the shaft, means normally tending to urge the rod in one direction, means for driving said shaft from the engine, speed responsive means mounted on the shaft and having a collar concentric with said rod and through which the latter passes, said collar having cam edge surfaces, and projections on the rod engageable with said surfaces, a finger adapted to engage the outer end of the rod for moving the same axially into the shaft, and manually operable means for actuating said finger.

50 14. In a supercharger as set forth in claim 13, further characterized by a yieldable connection between said manually operated means and said finger.

55 15. In a supercharger as set forth in claim 13, being further characterized by said engine being the means for driving said shaft and said compressor.

16. A supercharger as set forth in claim 12, further characterized by means actuated when certain transmission ratios are employed for controlling the movement of said manual operable means.

60 17. In a supercharger as set forth in claim 12, further characterized by a carburetor operatively connected with the engine, and means controlled by pressure in the carburetor for controlling the operation of the manually operable means.

65 18. In a supercharger as set forth in claim 12, further characterized by a carburetor operatively connected with the engine, and the fuel supply to the carburetor being controlled by the pressure of the output of the supercharger.

70 19. In a supercharger as set forth in claim 12, further characterized by a carburetor and ignition timing means operatively connected with the engine, and automatic means operated by the pressure output of the supercharger for retarding or advancing the timing of the ignition means of the engine and for regulating the needle valve of the carburetor of the engine.
